HANDLE AND LATCH COMBINATION FOR DOORS

Harry M. Riegelman, Rolling Hills, Calif., assignor to
Security Aluminum Corporation, Compton, Calif., a
corporation of California

Filed Aug. 16, 1961, Ser. No. 66,367

Term of patent 14 years

(Cl. D10—8)

FIGURE 1 is a perspective view of a handle and latch combination for doors embodying my new design;
FIGURE 2 is a top plan view;
FIGURE 3 is a side elevational view; and
FIGURE 4 is a front elevation view thereof.
The rear (not shown) is substantially plain.
The dominant features of my design reside in the portions shown in full lines.

I claim:

The ornamental design for a handle and latch combination for doors, substantially as shown and described.
